STEPHEN R. GLEASON, OF LOWELL, MASSACHUSETTS, ASSIGNOR TO WALTER L. PARKER COMPANY, A COPARTNERSHIP CONSISTING OF H. HUTCHINS PARKER AND ALLAN D. PARKER, OF LOWELL, MASSACHUSETTS.

SPOOL AND METHOD OF MAKING THE SAME.

Application filed December 8, 1926. Serial No. 153,324.

The present invention relates to an improved spool and method of making the same.

The object of the invention is to produce an improved construction of spool which will be strong, durable and inexpensive. To these ends the invention consists in the spool hereinafter described and particularly defined in the claims.

10 In the drawings illustrating the preferred form of the invention, Fig. 1 is an elevation of a spool, showing one end in longitudinal, medial section; Figs. 2 and 3 illustrate details of construction; Fig. 4 is an end view 15 of a spool, the outer portion of the head being broken away; and Fig. 5 is a longitudinal, medial section like that illustrated in Fig. 1, of a modified form of the invention.

The illustrated embodiment of the invention is described as follows: The barrel 1 is made of wood, and has a longitudinal central hole 2. The end of the barrel is provided with an annular extension or projection 3, which is received in an annular groove in the inside of the vulcanized fibre head 4. The head is provided with a central hole which is cylindrical about half the thickness of the head and tapered or frusto-conical for the remainder of the thickness of the head on the outside. A reinforcing ferrule 5 is made of brass or other metal and has a frusto-conical head portion 6, which is received in the hole in the head. The barrel of the ferrule is tapered at 7, and provided on its inner end with a ragged edge 8 which forms tooth-like projections. A bushing or plug 9 of dog-wood is employed inside of the ferrule and barrel of the spool, which has a head 10 of frusto-conical form which fits the frusto-conical head of the ferrule. The plug is provided at its center with a spindle hole 11.

The parts are assembled as follows: The head is fitted to the barrel, and the ferrule 5 is inserted in the hole in the head. The head and ferrule are then associated with the barrel in the position shown in Fig. 1, but it will be observed that the tapered portion 7 of the ferrule will then extend a conical surface inwardly into the hole in the barrel. Then the plug 9 will be forced in, and in the act of being forced into the hole in the ferrule and barrel it will expand the tapered portion 7 of the ferrule to a cylind-

rical form, as shown in Fig. 1, thereby 55 forcing the projections of the ragged edge of the ferrule into the wood of the barrel 1. Inasmuch as the ferrule is made of thin metal, its inner end will be cracked, perhaps, in places, and thus irregularly shaped portions of the inner end of the ferrule will be forced into the wood of the barrel, firmly bonding them together. The parts are covered with cement when they are assembled, and heavy pressure is exerted upon 60 the parts in order to force them tightly together, and then they are held under pressure until the cement sets.

The tapered end of the bushing is weakest to perform its function of holding the 70 head of the spool in place at its head 10, which, in the absence of the reinforcing ferrule, would be liable to be sheared off by the endwise pressure of the material wound on the spool, or by blows against the head 75 from one side or the other. Thus, if a blow were given the lower edge of the left hand end of the spool, as shown in Fig. 1, it would tend to shear off the upper portion of the head of the bushing or plug 9; if a blow were given the inside of the head near the 80 top, as shown in said figure, it would tend to shear off the same portion of the plug. The bushing, therefore, serves a useful purpose in conferring strength upon the spool 85 at the point where the fracture in use is most likely to occur in the absence of the bushing.

It is preferred to use a cement which will have strongly adhesive qualities not only for the purpose of uniting the wooden and fibre 90 parts together, but which also has the quality of forming a strong adhesive union with metal so that by its use all of the parts are strongly and adhesively united.

In the modification shown in Fig. 5, the 95 ferrule 12 is provided on its outer end with an outwardly extended flange having a portion at its extreme edge bent back and provided with a ragged edge which forms tooth-like projections to engage and enter the material of the head. The ferrule in this modification has tooth-like projections at both ends which lock the head and barrel firmly to each other to prevent rotation of the one on the other.

The present invention also contemplates the method of making spools above described, wherein the barrel and the head are

united by means of a plug or bushing and a reinforcing ferrule, according to which the ferrule is expanded in the assembling process. It is apparent that if the ferrule had 5 a cylindrical body portion which was forced into the inside of the barrel, it would plow its way through the wood if larger than the hole in the barrel, and therefore be more or less free to pull out upon slight provocation, 10 or, if the reinforcing ferrule were only the exact size of the hole in the ferrule, it would only be united to it by the cement. In accordance with the present method, not only is the cement used to hold the parts together, 15 but the ferrule is easily inserted in the hole in the barrel, and after insertion is expanded to cylindrical form so that it is forced radially outward against and into the wood of the inside of the barrel. It is believed that 20 this method secures the advantage of facilitating assembly of the spool as well as securing a stronger spool than otherwise would be possible.

Having thus described the invention, what 25 is claimed is:

1. A spool having a barrel with a cylin-

drical hole in its end, a head provided with a frusto-conical hole, a reinforcing ferrule having its outer end frusto-conical to fit the hole in the head and its inner end preliminarily frusto-conical and provided with outwardly extended projections, and a plug having its outer end frusto-conical to fit the inside of the ferrule and its inner end cylindrical to expand the inner end of the ferrule to fit the hole in the barrel and to force the projections on the inner end of the ferrule into the wall of the barrel hole, the barrel, head and plug being glued together. 30 35

2. The method of making the spool described in claim 1, which consists in making the inner end of the barrel of the ferrule frusto conical and expanding it to cylindrical form by forcing the bushing or plug into the ferrule while in position in the barrel, 40 in the act of assembling the parts, thereby causing the tooth-like projections on the inner end of the ferrule to penetrate the inner surface of the barrel. 45

In testimony whereof I have signed my name to this specification.

STEPHEN R. GLEASON.
